UNITED STATES PATENT OFFICE.

WILLIAM J. BARR, OF NORTH BENNINGTON, VERMONT, ASSIGNOR TO THE H. T. CUSHMAN MFG. CO., OF NORTH BENNINGTON, VERMONT, A CORPORATION OF VERMONT.

DESIGN FOR A SMOKER'S STAND.

Application filed October 17, 1927. Serial No. 23,768. Term of patent 3½ years.

To all whom it may concern:

Be it known that I, WILLIAM J. BARR, a citizen of the United States, residing at North Bennington, in the county of Bennington and State of Vermont, have invented a new, original, and ornamental Design for a Smoker's Stand, of which the following is a specification, reference being had to the accompanying drawings, forming part thereof.

Drawings:

The figure is a perspective view of a smoker's stand showing my new design.

I claim:

The ornamental design for a smoker's stand substantially as shown.

WILLIAM J. BARR.
